[57] CLAIM

The ornamental design for a wrist exerciser, as shown and described.

DESCRIPTION

FIG. 1 is a side elevational view of a wrist exerciser showing our new design, the side opposite being identical;

FIG. 2 is an end elevational view thereof;

FIG. 3 is an end elevational view of the end opposite that shown in FIG. 2;

FIG. 4 is a front elevational view of a modified embodiment of the design shown in FIGS. 1 through 3;

FIG. 5 is a right side elevational view thereof; and,

FIG. 6 is a left side elevational view thereof.

Fig. 1.

Fig. 2.

*Fig.5.**Fig.3.**Fig. 4.*

Fig. 6.
